(57) **CLAIM**

The ornamental design for a sun lounger, as shown and described.

DESCRIPTION

FIG. 1 is a front and top perspective view of a sun lounger, showing the first embodiment of my new design;

FIG. 2 is a front and bottom perspective view thereof;

FIG. 3 is a front view thereof;

FIG. 4 is a rear view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of the portion taken at line-9 in FIG. 2;

FIG. 10 is a front and top perspective view of a second embodiment of a sun lounger, showing my new design;

FIG. 11 is a front view thereof;

FIG. 12 is a rear view thereof;

FIG. 13 is a left side elevation view thereof;

FIG. 14 is a right side elevation view thereof;

FIG. 15 is a top plan view thereof; and,

FIG. 16 is a bottom plan view thereof.

The broken lines depict portions of the sun lounger in which the design is embodied that form no part of the claimed design.
